UNITED STATES PATENT OFFICE.

ROBERT T. HUNT, OF COSHOCOTON, OHIO, ASSIGNOR TO THE HUNT-CRAWFORD CO., OF COSHOCOTON, OHIO, A CORPORATION OF OHIO.

ICE-CREAM CONTAINER.

1,376,770.

Specification of Letters Patent. Patented May 3, 1921.

Application filed August 2, 1919. Serial No. 314,974.

To all whom it may concern:

Be it known that I, ROBERT T. HUNT, a citizen of the United States, and resident of Coshocton, in the county of Coshocton and State of Ohio, have invented a new and useful Improvement in Ice-Cream Containers; and I do hereby declare the following to be a full, clear, and exact description thereof.

My invention relates to an ice-cream container for delivering ice-cream or ices from the factory to the consumer.

Under the system now generally in vogue in delivering ice-cream from the factory to the consumer the ice-cream is placed in a can and the can introduced into a wooden tub or bucket, whereupon ice is packed around the can and well over the top to prevent the ice-cream from melting in transit and until ready to be served. The cost of the tin receptacle, the wooden bucket and the packing of the ice around the same is a matter of great expense, and forms a heavy cumbersome article to be delivered, while the bulk takes up a great deal of room in the delivery wagon. Furthermore, after the delivery of the ice-cream, the buckets and cans have to be called for to be returned to the factory, and in the meantime very often the lid of the can has become misplaced or lost, and through pressure of business very often the return of the bucket and can is delayed so that very often both are missing when they are called for, and as a consequence great loss and inconvenience is occasioned by this system.

The object of my invention is to provide a compact light package in which the ice-cream is delivered and in which it can be kept in a frozen state for hours without the employment of any ice. The container being formed of cardboard when once used may be destroyed or thrown away, thereby dispensing with all the expense and inconvenience of the return of the container to the factory.

To these ends my invention comprises the novel features hereinafter set forth and claimed.

In the accompanying drawing Figure 1 is a longitudinal sectional view of my improved container ready for shipment; Fig. 2 is a cross section of same on the line 2—2 Fig. 1; Fig. 3 is a perspective view of one of the disks of the container.

In the drawing the numeral 2 designates

the outer container which is formed of pasteboard or other material of a like character which will have the necessary strength and rigidity, but which can be produced at low cost. In the bottom of the outer container 2 is located a disk 3 formed of corrugated paper board composed of a layer of corrugated board and then a plain layer. In this manner the air spaces between the layers of the disk form air cells which provide a dead-air space at the bottom of the outer container 2.

To provide a like dead-air space around the inner walls of the container 2 and the inner container 4, I provide a roll of corrugated paper 5 in the form of a shell made up of several spirally wound convolutions and into which the inner container 4 is inserted. The air cells of the surrounding corrugated cylinder provide for the insulation of the walls of the inner container 4.

The inner container 4 is provided with the lid 6.

Resting on the lid 6 of the inner container is the disk 7 of the same construction as the disk 3 which provides for the insulation of the top of the container.

The outer container is provided with the lid 8.

When the inner container 4 is filled with ice-cream the cover 6 is applied and the container is inserted into the outer container with its bottom resting upon the disk 3 and its outer walls surrounded by the corrugated roll 5. The top disk 7 is then applied and the cover 8 adjusted on the outer container, whereupon the container is ready for transportation.

Practical experience has proven that ice-cream transported in my improved container will keep for many hours in a hard frozen condition, as the inner container is completely enveloped by the dead-air spaces which insulate the inner container from the heat.

By my invention I provide an ice-cream container which is compact in form, light in weight and yet sufficiently durable to stand the rough treatment which such containers may receive in handling and transportation. The ice-cream is kept in a hard frozen state without the use of any ice, consequently there is not the constant dripping of water which takes place where the ice cream is transported in buckets of ice. Fur- 110

thermore, from a sanitary standpoint, there is a great advantage in the use of a single service package.

After the ice-cream has been delivered 5 and removed from the container the container may be destroyed or thrown away, thereby dispensing with all the expense and trouble of collecting the buckets and cans heretofore employed for this purpose, and 10 returning them to the factory.

What I claim is:—

An ice-cream container comprising a cylindrical outer container formed of pasteboard or like material, a corrugated paper

board disk at the bottom of said outer container, a cylindrical shell formed of a plurality of spirally wound convolutions of corrugated paper board and fitting within said outer container, a removable inner container of pasteboard or like material, a disk on top 15 of said inner container, and a lid for said outer container.

In testimony whereof, I, the said ROBERT T. HUNT, have hereunto set my hand.

ROBERT T. HUNT.

Witnesses:

ROBT. D. TOTTEN.

JOHN F. WILL.
